WEB TENSION MECHANISM

Kenneth G. Laycock, Shavertown, Pa.

Application February 25, 1953, Serial No. 338,696

11 Claims. (Cl. 242—75)

The present invention relates to web tensioning devices for automatically controlling the tension of a paper web as it is fed from a web roll to a rotary printing press and has specific relation to new and useful improvements in web tensioning devices of the type shown and described in my Patent No. 2,637,505 issued May 5, 1953.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a side elevation of a typical and preferred embodiment of the present invention;

Figure 2 is a sectional view taken along line 2—2 of Figure 1; and

Figure 3 is a side elevation similar to that of Figure 1 but looking from the other side of the device.

The present invention has for its object the provision of a web tensioning device that is relatively simple and inexpensive to manufacture yet highly satisfactory and reliable in its operation of maintaining a uniform tension on the web of paper as it is drawn from the web roll and fed into the rotary printing press. A further object is to provide a web tensioning device with novel means effective to maintain the web at a substantially uniform tension even though the web roll is out of round or otherwise irregular.

In accordance with a preferred embodiment of the present invention a roll of paper is rotatably mounted in a suitable frame and a web is fed from the roll into a rotary printing press passing over a pilot roller on its way to the press. The pilot roller is rotatably mounted between a pair of arms that are secured to a shaft which is journaled in upright frame members, and through this mounting means the pilot roller is moved about the axis of said shaft by changes in web tension. The tension of the web is governed by brake means operable to frictionally resist rotation of the web roll and the operation of this brake means is regulated by the pilot roller through suitable linkage mechanism arranged so that when the pilot roller is moved by an increase in web tension the brake applied friction is decreased and vice versa.

The force which the web tension exerts against the pilot roller is opposed by the weight of a mass of considerable magnitude which acts through the shaft to which the pilot roller supporting arms are connected to urge the pilot roller in a direction opposite to that in which the web urges the pilot roller. This mass is connected to the shaft through a pivoted lever, the pivotal support for

2

which is a spring biased lever provided with a curved supporting arm and pivoted to a bracket member that is journaled to the shaft. Means are provided for securing the bracket member to the shaft at any desired angular position about the shaft. Angular movement of the bracket with respect to the shaft has the effect of varying the leverage ratio of the spring biased lever whereby the lever is able to support masses of varying magnitude without changing the magnitude of the spring bias applied to the lever.

It will be understood that the foregoing general description and the following detailed description as well are exemplary and explanatory of the invention but are not restrictive thereof.

Referring now to the drawings, wherein like numerals are used throughout to designate like elements, the illustrative and preferred embodiment shown therein comprises a web roll 10 wound about shaft 12 which is rotatably supported at each end in spaced members 14 which extend laterally from upright frame members 16. A web of paper 19 is drawn from the roll serially passing under guide roller 18, over pilot roller 20 and under guide roller 22, after which it enters the rotary printing press not here shown. Tension is created in web 19 by means of a brake which comprises brake drum 24 and brake shoes 26. The brake shoes are pressed toward each other and into contact with drum 24 by means of lever arms 28 which are pivotally supported by a link 30 mounted on spaced frame member 14 by means of the side lay adjusting wheel 32. The other ends of levers 28 are interconnected by means of turnbuckle link 34, the upper end of which is connected to a bell crank 36 having a long upwardly extending arm 38 and a short lever arm 40, the short lever arm detachably connecting the upper end of link 34 with the adjacent end of upper lever arm 28. The length of link 34 may be varied to compensate for wear of brake shoes 26 by turning hand wheel 42 which will thread the rod that forms a part of the link into or out of the link end members.

The frictional force exerted by the brake to tension web 19 is accurately regulated by pilot roller 20 which is rotatably supported intermediate spaced arms 44 which in turn are pivoted in upright frame members 16 by means of shaft 46 and are preferably counterbalanced by means of variably positionable weight 48. Shaft 46 is fastened to each of the arms 44 by means of pins 51 (Figure 2) and is mounted in bearings 50 secured within suitable openings provided in the spaced upright frame members 16. One end of the shaft that projects beyond one of the frame members is provided with depending arm 52 keyed to the shaft at a fixed angular position relative to arms 44 and connected to arm 38 of bell crank 36 through link 54.

The brake mechanism and its interconnection with pilot roller 20 is such that when an increase in web tension causes the pilot roller to move downward bell crank 36 is moved counterclockwise as viewed in Figure 3 to lessen the pressure that brake shoes 26 exert against brake drum 24 causing a reduction in the frictional resistance opposing the rotation of web roll 10 and resulting in lessening the tension of web 19. Similarly a decrease in the tension of the web causes a reverse movement of these parts so that the pressure exerted by shoes 26 is increased to increase the web tension. The action of pilot roller 20 in response to variations in web tension is therefore such that the tension of web 19 is maintained substantially uniform.

The force which web 19 exerts against pilot roller 20 urging the roller downward is opposed by relatively large mass 56 acting through shaft 46 by means of a linkage arrangement having a spring biased pivotal support. The linkage arrangement comprises arm 58 keyed

by changing the weight of mass 56 and fine adjustments being made by moving member 66.

While spring mechanism 62 is here disclosed as embodied in an installation wherein it is desirable to adjust the mechanism so as to maintain a substantially constant spring compression for varying load conditions it is to be understood that this mechanism is also applicable to installations where it is desirable that the applied force of the spring be varied.

The invention in its broader aspects is not limited to the specific mechanism shown and described but departures may be made therefrom within the scope of the accompanying claims without departing from the principles of the invention and without sacrificing its chief advantages.

What is claimed is:

1. In a shock absorbing spring mechanism adapted to provide a readily adjustable leverage ratio acting upon the spring of the mechanism the combination of a rotatable shaft, an arm mounted on the shaft, a lever pivotally secured at one end of the arm, said lever adapted to have a load applied thereto, a generally cylindrical bracket member mounted on said shaft, means securing said bracket to said shaft at desired angular positions, said bracket having a pair of angularly spaced outwardly projecting ears, a second lever pivotally connected intermediate its ends to one of said ears for pivotal movement about an axis generally parallel to said shaft, at least a portion of the lever on one side of said pivotal connection being curved and generally concentric with said shaft, the other of said ears having an opening therein with a spring rod projecting therethrough and pivotally connected to the extremity of the portion of the lever on the other side of said pivotal connection, a cam follower on the first-mentioned lever bearing on the curved portion of the second lever and a coil spring disposed over said rod and compressed between the free end of the rod and the ear through which the rod projects.

2. In a web tensioning device for controlling the tension of a web drawn from a web roll, means for applying friction to the web roll to tension the web, and a pilot roller moved by changes in web tension and connected to increase or decrease the friction applied to the web roll, an increase in web tension causing a decrease in the friction, the combination of a mass connected to the pilot roll through a pivotally supported lever and operable to urge the pilot roll against the tension of the web, the pivotal support for said lever comprising a pivoted lever spring biased to oppose the weight of said mass acting at the point of pivotal support of the first mentioned lever, said spring biased lever being movable with respect to said point of pivotal support to change the leverage ratio of the spring biased lever thereby changing the effectiveness of the spring bias.

3. A web tensioning device as claimed in claim 2 including means to adjust the position of the mass relative to the point of pivotal support of the first mentioned lever.

4. In a web tensioning device for controlling the tension of a web drawn from a web roll, means for applying friction to the web roll to tension the web, and a pilot roller moved by changes in the web tension and connected to increase or decrease the friction applied to the web roll, an increase in web tension causing a decrease in the friction, the combination of a mass connected to the pilot roll through a pivotally supported lever and operable to urge the pilot roll against the tension of the web, the pivotal support for said lever including a pivotally mounted member having a curved support arm, means operable to secure the pivotal mounting for said member at desired angular positions about a given axis generally parallel with the pivotal axis of the member, the arm of said member being curved about said given

axis, and resilient means effectively disposed between the member and its mounting urging the arm against the bias of the weight of the mass.

5. A web tensioning device as claimed in claim 4 in which the curved supporting arm is concentric with the given axis.

6. A web tensioning device as claimed in claim 4 in which the resilient means is a spring having means to adjust the force that it exerts upon said member.

7. In a web tensioning device for controlling the tension of a web drawn from a web roll, the combination of friction means restraining the rotation of the web roll, a shaft mounted for rotation about a given axis, a pair of coplanar spaced arms secured to said shaft, a pilot roller rotatably mounted intermediate said arms and moved about said given axis by changes in tension of the web, means effective to impart movements of said roller to the friction means to increase the applied friction upon a decrease in web tension and decrease said friction upon an increase in web tension, an arm secured to said shaft, a lever pivotally connected to said arm, said lever supporting a mass, means pivotally supporting said lever so the weight of said mass is effective to urge the pilot roll against the tension of the web, the pivotal support including a bracket rotatably mounted on said shaft, means for securing said bracket at desired angular positions about said shaft, lever means pivoted to said bracket about an axis generally parallel with said given axis, said lever having an arm curved about said given axis and upon which the first mentioned lever is supported, spring means effectively disposed between the bracket and the second mentioned lever operable to urge the same in opposition to the action of the weight of the mass at the point of pivotal support of the first mentioned lever.

20 8. A web tensioning device as claimed in claim 7 in which said curved arm is concentric with said given axis.

25 9. A web tensioning device as claimed in claim 7 in which means are provided for adjusting the force which the spring exerts upon the second mentioned lever.

30 10. A spring mechanism for a web tensioning device comprising a rotatable shaft, an arm mounted on the shaft and rotatable in one direction to increase the tension on the web and in the opposite direction to decrease the tension on the web, a lever pivotally secured at one end to the arm, said lever having a load applied thereto in a direction tending to rotate the arm in a web tension-increasing direction, a cam follower on the lever, a second pivoted lever mounted to engage the cam follower on the first-mentioned lever, said second lever having an adjustable pivot whereby the distance between the cam follower of the first-mentioned lever and said pivot may be varied to change the leverage ratio of the load bearing on the second-mentioned lever through the cam follower, and a spring secured to one end of the second lever to oppose movement of said second lever in a web tension-decreasing direction.

35 11. A spring mechanism for a web tensioning device as set forth in claim 10 in which the pivot for the second lever is mounted on a bracket rotatable with the shaft, the pivot being adjustable by said bracket being adjustable with respect to the shaft so as to vary the distance between the cam follower and said pivot.

40 12. A web tensioning device for controlling the tension of a web drawn from a web roll, means for applying friction to the web roll to tension the web, and a pilot roller moved by changes in the web tension and connected to increase or decrease the friction applied to the web roll, an increase in web tension causing a decrease in the friction, the combination of a mass connected to the pilot roll through a pivotally supported lever and operable to urge the pilot roll against the tension of the web, the pivotal support for said lever including a pivotally mounted member having a curved support arm, means operable to secure the pivotal mounting for said member at desired angular positions about a given axis generally parallel with the pivotal axis of the member, the arm of said member being curved about said given

45 13. A web tensioning device as claimed in claim 12 in which the curved supporting arm is concentric with the given axis.

50 14. A web tensioning device as claimed in claim 12 in which the resilient means is a spring having means to adjust the force that it exerts upon said member.

55 15. In a web tensioning device for controlling the tension of a web drawn from a web roll, the combination of friction means restraining the rotation of the web roll, a shaft mounted for rotation about a given axis, a pair of coplanar spaced arms secured to said shaft, a pilot roller rotatably mounted intermediate said arms and moved about said given axis by changes in tension of the web, means effective to impart movements of said roller to the friction means to increase the applied friction upon a decrease in web tension and decrease said friction upon an increase in web tension, an arm secured to said shaft, a lever pivotally connected to said arm, said lever supporting a mass, means pivotally supporting said lever so the weight of said mass is effective to urge the pilot roll against the tension of the web, the pivotal support including a bracket rotatably mounted on said shaft, means for securing said bracket at desired angular positions about said shaft, lever means pivoted to said bracket about an axis generally parallel with said given axis, said lever having an arm curved about said given axis and upon which the first mentioned lever is supported, spring means effectively disposed between the bracket and the second mentioned lever operable to urge the same in opposition to the action of the weight of the mass at the point of pivotal support of the first mentioned lever.

60 16. A web tensioning device as claimed in claim 15 in which said curved arm is concentric with said given axis.

65 17. A web tensioning device as claimed in claim 15 in which means are provided for adjusting the force which the spring exerts upon the second mentioned lever.

70 18. A web tensioning device as claimed in claim 15 in which the resilient means is a spring having means to adjust the force that it exerts upon said member.
